UNITED STATES PATENT OFFICE

150,948

DESIGN FOR A NONMETALLIC TEMPLE FOR SPECTACLES OR SIMILAR ARTICLE

Julius E. Hansen, Providence, R. I., assignor to
Bay State Optical Company, Attleboro, Mass.,
a corporation of Maine

Application March 18, 1947, Serial No. 137,695

Term of patent 14 years

(Cl. D57—1)

To all whom it may concern:

Be it known that I, Julius E. Hansen, a citizen of the United States and a resident of Providence, in the county of Providence, State of Rhode Island, have invented a new, original, and ornamental Design for a Non-metallic Temple for Spectacles or Similar Article, of which the following is a specification, reference being had to the accompanying drawing, forming a part hereof.

In the drawing,

Figure 1 is a side elevational view of a non-metallic temple for spectacles, showing my new design;

Figure 2 is a top plan of the temple shown in Figure 1; and

Figure 3 is a rear elevation of the temple shown in Figure 1.

I claim:

The ornamental design for a non-metallic temple for spectacles or similar article, substantially as shown.

JULIUS E. HANSEN.
